ART OF REFINING

George Thayer, East Chicago, Ind., assignor to
 Sinclair Refining Company, New York, N. Y., a
 corporation of Maine

Application August 6, 1937, Serial No. 157,748

3 Claims. (Cl. 196—13)

This invention relates to the treatment of hydrocarbon oils and more particularly to the solvent extraction of lubricating oils. The process of this invention provides an improved and efficient method of contacting hydrocarbon lubricating oils with a selective solvent.

Heretofore, solvent extraction of hydrocarbon lubricating oils has been effected by thoroughly agitating the oil and solvent under suitable conditions of temperature and pressure in a mixing chamber and subsequently separating the extract and raffinate phases in a separate operation. Such a process as this has necessitated a large amount of apparatus for mixing the oil and solvent and for separating the extract and raffinate phases.

It has also been proposed to effect solvent extraction of lubricating oils by introducing the solvent and untreated oil into the top and bottom, respectively, of a baffled tower. As a further modification, solvent extraction of the oil has been effected by introducing the oil into the central portion of a vertical tower and introducing a heavy solvent into the top and a light solvent into the bottom of the tower. In such operation the mixture of oil and solvent or solvents completely fills the entire space within the tower, and contact between solvent and oil is effected by countercurrent flow of the solvent or solvents and oil due to their relative difference in gravity. Where gravity towers such as these have been used it has usually been necessary for satisfactory results that a plurality of towers be arranged in series in order that the final raffinate be sufficiently refined. Whenever it has been necessary to repair or to clean any one of the gravity towers the operation of the entire series has been discontinued, thus resulting in an obviously uneconomical use of a large amount of equipment.

The process of my invention provides a simple and efficient operation whereby satisfactory separation may be effected in a single stage using a simple and extremely compact apparatus as compared with apparatuses heretofore necessary. By the use of the process of my invention, a solvent extraction plant constructed with a number of these compact machines operating in parallel would not have its capacity seriously handicapped if one or even more of the machines were shut down for cleaning.

More particularly, the process of my invention contemplates subjecting the oil to be treated and a suitable solvent or solvents to the action of centrifugal force to produce an extract and a raffinate phase, and withdrawing the extract and

raffinate phases. The oil and the solvent or solvents may be separately introduced into a centrifuge. The extract and raffinate phases produced within the centrifuge by the contact between the oil and solvent upon subjection to centrifugal force may be separately withdrawn from the centrifuge.

The process of my invention will be more clearly understood by a consideration of the apparatus in which the process is carried out. A typical form of apparatus is shown in Figure 1 of the accompanying drawings which comprises a sectional view of a centrifuge in which an oil may be subjected to selective extraction;

Figure 2 comprises a sectional view of a modified form of centrifuge; and

Figure 3 comprises a horizontal sectional view of the stationary and revolving bowls of the centrifuges.

The centrifuge shown in Figure 1 comprises a stationary bowl 1 provided with a cover divided radially into two non-communicating chambers 2 and 3. A revolving bowl 4 provided with a cover member 5 is positioned coaxially within the stationary bowl and is rotatably mounted therein. Two sets of concentric cylinders 6 and 7 are placed within the revolving bowl 4, and these sets of concentric cylinders are positioned so as to alternately overlap each other, thus forming a series of annuluses. One end of one set of cylinders is rigidly mounted in the false bottom 8 of the revolving bowl and one end of the other set of cylinders is rigidly mounted in the false cover 10 of the cover member 5. Suitable means may be provided on the inner surface of the false cover 10 and of the false bottom 8 of the revolving bowl for removably holding the unmounted ends of each of the sets of concentric cylinders securely in position. The unmounted ends of the cylinders are provided with suitable perforations 11 and 12 to allow the passage of a fluid therethrough. Perforations 13 and 14 are provided in the false cover and false bottom, respectively, of the revolving bowl to permit the passage of a fluid from the interior of the revolving bowl into the space between the false cover and false bottom, respectively, and the outer shell of the revolving bowl, which space is maintained by perforated spacer rings 15 and 16, respectively. The centers of the false cover and the false bottom terminate in concentric cylinders 17 and 18, respectively, which extend into the cover portion of the stationary bowl. An additional cylinder 19 extends coaxially from within the cover portion of the stationary bowl between cylinders 17 and 18.

- and 18 to a position well within the interior of the revolving bowl. Cylinder 17 communicates with the upper section 2 of the cover portion of the stationary bowl while cylinders 18 and 19, respectively, communicate with suitable supply pipes 20 and 21. The desired space between the concentric cylinders 17 and 19 and between the concentric cylinders 18 and 19 is provided by perforated spacer rings 22 and 23, respectively.
- 10 The collar 24 of cover member 5 extends within section 3 of the stationary bowl cover portion and provides a communicating space, together with cylinder 17, for fluid to pass from the space maintained by spacer rings 15 into section 3.
- 15 Discharge spouts 25 and 26 are provided for the removal of fluid from each of sections 2 and 3 of the cover portion of the stationary bowl. Supply pipes 20 and 21 may be provided with advantage with valves (not shown) for controlling the rate 20 of flow of liquid through these pipes. Suitable means may be provided with advantage for draining from the space between stationary bowl 1 and revolving bowl 4 any fluid which may have leaked thereinto.
- 25 In carrying out the process of my invention, in the apparatus shown in Figure 1, the oil to be treated is introduced into the centrifuge through supply pipe 20 into cylinder 18, thence through spacer rings 16 and perforations 14 into the outer 30 portion of the interior of the revolving bowl. The solvent or suitable solvent mixture with which the oil is to be treated and usually heavier than the oil is introduced into the centrifuge through supply pipe 21, thence into the space between cylinders 18 and 19 through spacer rings 23 and into the central portion of the interior of the revolving bowl. The revolving bowl is rotated by means of shaft 27 thus exerting centrifugal force on the oil and solvent. The solvent, being heavier than the oil, displaces the oil at the outer portion 40 of the revolving bowl and forces the oil toward the center of the bowl. As the oil is forced toward the center of the bowl, it passes through a tortuous path as it flows through the annuluses and the perforations 11 and 12 alternately positioned at the top and bottom, respectively, of adjacent concentric cylinders 6 and 7. Thus, the oil being forced toward the center of the bowl and the solvent being forced toward the outer 50 edge of the bowl come into contact as they pass through the annuluses. The solvent, as it approaches the outer edge of the revolving bowl, comprises a solution of the extract in the solvent, while the oil forced toward the center of the bowl 55 comprises the refined oil or raffinate phase. The position of the interface, which is indicated by the dotted line 28, between the oil and the extract phases in the outer portion of the revolving bowl is controlled with advantage by the internal diameter of replaceable ring dams 29 and 29'. The position of the interface is moved toward the center of the bowl by decreasing the internal diameter of ring dam 29, or, conversely, is moved toward the outer portion of the bowl by increasing 60 the internal diameter of ring dam 29. Variation in the internal diameter of ring dam 29' has a diametrically opposite effect upon the position of the interface to that of ring dam 29. The position of the interface may, therefore, be controlled by changing the internal diameter of ring dam 29 or 29', or by the combined effect of both.
- 65 The oil being forced toward the center by the extract phase tends to fill the greater portion of the bowl. The heavier solvent, or extract phase as it soon becomes, flowing counter-currently out- 70 ward with respect to the oil flows upward or downward, as the case may be, on the outer edge of each annular space seeking its way to the outer portion of the bowl. At the lip of each cylinder, formed by the perforations 11 and 12, the out-flowing solvent (or extract) phase and the inflowing oil (or raffinate) phase undergo instantaneous mixing and are separated again by centrifugal force in the next succeeding annular space. As a result of this counter-current flow 75 and instantaneous mixing, each annular space with the lip of the cylinders within the revolving bowl comprises a stage in a counter-current system. The extract phase collected at the outer portion of the revolving bowl passes through perforations 13 through spacer rings 15 into section 3 of the cover portion of the stationary bowl. The raffinate phase forced toward the center of the bowl flows upwardly through spacer rings 22 into section 2 of the cover portion of the stationary bowl. Thus, the operation comprises a process in which the oil to be treated and solvent are introduced separately into a centrifuge and separate extract and raffinate phases are discharged from the apparatus.
- 25 The modified form of apparatus shown in Figure 2 is adapted for use in a process wherein the oil to be treated is subjected to the action of two individual selective solvents. The apparatus itself is substantially the same as that shown in Figure 1. The modified apparatus, however, is provided with an additional cylinder 30 extending coaxially within cylinder 18 and conforming generally to the shape of cylinder 18 and false bottom 8 of the revolving bowl. The lower extension 31 of the cylinder 30 engages at its outermost end the false bottom 8 at a point substantially half way between the center and outer portion 35 of the revolving bowl. The false bottom is further provided with perforations 32 to permit the passage of a fluid into the interior of the revolving bowl from the space between the lower extension 31 and false bottom 8. This space between lower extension 31 and false bottom 8 is maintained by perforated spacer rings 33, while the space between concentric cylinders 18 and 30 is maintained by suitable spacer rings 34. The upper portion of cylinder 30 communicates with a suitable supply pipe 35 which may be provided with a suitable valve (not shown).
- 50 In carrying out the process of my invention in the modified form of apparatus shown in Figure 2, the oil to be treated is introduced into the centrifuge through supply pipe 20 into the space between cylinders 18 and 30, thence through spacer rings 34 and 33 and perforations 32 into the bowl substantially half way between the center and outer portion thereof. A heavy solvent such, for example, as phenol may be introduced through supply pipe 21 and spacer rings 23 60 into the center portion of the revolving bowl. A suitable light solvent such as a light naphtha or the like is introduced through supply pipe 35 into cylinder 30, thence through spacer rings 16 and perforations 14 into the outermost portion of the revolving bowl. Upon rotation of the revolving bowl by means of shaft 27, a centrifugal force of considerable magnitude may be exerted upon the oil and solvents within the bowl. The heavy solvent is forced toward the outer portion of the revolving bowl together with the heavy extract obtained from the oil by contact between the oil and the solvents. The lighter solvent is displaced from the outer portion of the revolving bowl and is forced toward the center of the bowl.

together with the raffinate produced by contact of the oil and solvents. The extract flows through perforations 13 and spacer rings 15 into section 3 of the cover portion of the stationary bowl, while the raffinate is forced upwardly through spacer rings 22 into section 2 of the cover portion. If desired, the entire apparatus may be maintained under a superatmospheric pressure by enclosing the apparatus in a suitable pressure chamber. Thus, the modified operation carried out in the apparatus shown in Figure 2 comprises a process in which the oil to be treated and two individual solvents are introduced separately into a centrifuge and separate extract and raffinate phases are discharged from the apparatus.

If it is found desirable to maintain a substantially uniform revolving speed of fluid within the apparatus shown in Figures 1 and 2, the rotatable bowl may be provided with a plurality of vertical radial partitions 36 as shown in Figure 3. These vertical radial partitions may extend substantially the entire distance between false bottom 8 and false cover 10 of the rotatable bowl and also extend substantially the entire distance between cylinder 18 and the outer shell 4 of the revolving bowl.

While the process of my invention has been described above with respect to the treatment of unrefined oil, it must be emphasized that my invention is also applicable to the treatment of an oil which is saturated or partially saturated with a solvent. For example, if a plurality of centrifugal machines are to be connected in series so that the raffinate from the first machine is introduced into the second machine as the stock to be treated, this stock which is fed into the second and subsequent machines will comprise a refined or partially refined oil containing a substantial quantity of solvent or solvents. Moreover, it may be desirable, under certain conditions such as the relative densities of the oil to be treated and the solvent or solvents, to mix the raw oil with one or more of the treating solvents, or even a different solvent, before introducing the raw oil into the machine. In such a case, the mixture of raw oil and solvent or solvents charged into the machine as stock to be treated would have a substantially higher density than that of the raw oil alone, thus effecting a decrease in power consumption required to maintain the rotational speed of the revolving bowl. Therefore, the expressions "oil" and "oil to be treated" appearing in the specification and claims should be interpreted as including an oil saturated or partially saturated with one or more solvents.

As a further modification, the apparatus shown in Figure 2 of the drawings may be used with particular advantage for the precipitation of a secondary raffinate for retreatment. In such an operation, the precipitating medium is introduced through supply pipe 35. When the heavy solvent comprises furfural or phenol, for example, water may be used as the precipitating medium, while alcohol, cellosolve, or the like, may be used as the precipitating medium when the heavy solvent comprises phenol or nitrobenzene, for example.

Many advantages are realized from the use of the process of my invention. An efficient and complete separation of the extract and raffinate

phases is produced by the centrifugal force set up within the centrifuge. Inasmuch as the greater bulk of the fluid substantially completely filling the entire revolving bowl comprises the oil (or raffinate), a thin film of the solvent (or extract) is maintained at the outer edge of each annular space. The thin film thickness of the extract at the outer portion of each annular space together with the forceful mixing at the lip of each of the concentric cylinders within the bowl produce a highly efficient mixing of the oil and solvent.

The compactness and simplicity of the centrifuge conserves space and simplifies the operation as well as cleaning of the apparatus.

Moreover, inasmuch as the process of this invention thoroughly mixes the oil and solvent and efficiently separates the extract and raffinate phases, the treatment with a single machine may constitute with advantage the complete treatment of the oil. A solvent plant using the process of this invention carried out in a number of centrifuges operating in parallel, therefore, would not be seriously handicapped with respect to its overall capacity if one or even several machines were shut down for cleaning or repairs.

I claim:

1. In the solvent extraction of hydrocarbon lubricating oils, the improvement which comprises introducing a selective solvent into the central portion of a centrifuge, introducing an additional selective solvent into the outer portion of the centrifuge, introducing the oil to be treated into the centrifuge at a point intermediate the points of introduction of the two selective solvents, subjecting the oil and solvents to the action of centrifugal force to produce an extract and a raffinate phase, and separately withdrawing the extract and raffinate phases.

2. In the solvent extraction of hydrocarbon lubricating oils, the improvement which comprises introducing a relatively heavy selective solvent into the central portion of a centrifuge, introducing a relatively light selective solvent into the outer portion of the centrifuge, introducing the oil to be treated into the centrifuge at a point intermediate the points of introduction of the selective solvents, subjecting the oil and solvents to the action of centrifugal force to produce an extract and a raffinate phase, and separately withdrawing the extract and raffinate phases.

3. The method of securing counter-current contact between a relatively heavy fluid, a relatively light fluid, and a fluid having a density intermediate that of the heavier and lighter fluids which comprises introducing the heavier fluid into the innermost of a plurality of laterally closed passageways of increasing radius, said passageways having non-aligned openings, introducing the lighter fluid into the outermost passageway, introducing the fluid of intermediate density into a passageway intermediate the innermost and outermost passageways, and rotating the passageways to exert centrifugal force on these fluids to produce counter-current flow of the lighter and heavier fluids therethrough while in contact with the fluid of intermediate density.

GEORGE THAYER.
